UNITED STATES PATENT OFFICE.

LEVI BROWN, OF CLARINDA, IOWA, ASSIGNOR TO CLARINDA LAWN MOWER COMPANY,
OF CLARINDA, IOWA, A CORPORATION OF IOWA.

DRIVING MECHANISM.

1,135,496.

Specification of Letters Patent. Patented Apr. 13, 1915.

Application filed May 13, 1914. Serial No. 838,265.

To all whom it may concern:

Be it known that I, LEVI BROWN, a citizen of the United States of America, and resident of Clarinda, Page county, Iowa, 5 have invented a new and useful Driving Mechanism, of which the following is a specification.

The object of this invention is to provide an improved construction and arrangement 10 for mechanisms for driving the agitating devices of a washing machine.

A further object of this invention is to provide an improved mechanism for imparting alternating rotary motion to a 15 driven shaft.

A further object of this invention is to provide a dolly driving mechanism which shall be simple in construction and eminently quiet and efficient in operation.

20 My invention consists in the construction, arrangement and combination of elements hereinafter set forth, pointed out in my claims and illustrated by the accompanying drawing, in which—

25 Figure 1 is a rear elevation illustrating my improved driving mechanism applied to a washing machine, the gear housing or dolly box being shown in section to reveal interior construction. Fig. 2 is a plan of the same. Fig. 3 is a vertical section, on an enlarged scale, illustrating the clutch connections between the power shaft and countershaft. Fig. 4 is an elevation, on an enlarged scale, of a sleeve surrounding and 35 adapted to drive the dolly shaft. Fig. 5 is a fragmentary plan, on an enlarged scale, illustrating means for stopping the sleeve and dolly shaft at the end of each partial revolution.

40 In the construction and mounting of the mechanism as shown the numeral 10 designates a support such as a washing machine tub of any desired construction and carried in any desired manner. The tub 10 is formed with a stationary cover member 11 and a movable cover member 12. Hinge members 13 are fixed to the stationary cover member 11 and are inclined upwardly and laterally therefrom, and similar hinge members 14 are fixed to the movable cover member 12 and are inclined upwardly and laterally therefrom to register with the first hinge members. A power shaft 15 is journaled for rotation in the upper ends of the 45 hinge members 13, 14 and said shaft also

constitutes a pintle for articulation of the hinge members 14 and movable cover member 12. The line of articulation of the cover member 12 is considerably above the plane of the fixed cover member 11 and approximately in the vertical plane of the outer margin thereof, so that the movable member 12 swings entirely out of the way when in open position, and affords easy access to the tub.

50 A bracket 16 is mounted on one side of the tub 10 and a prime mover, such as an electric motor 17, is loosely mounted on and supported by said bracket, and has driving connections, through spiral gears mounted 60 in a gear case 18, with the shaft 15. A dolly shaft 19 is mounted for rotary oscillation in upright position in the center of the tub 10 and projecting through the movable cover member 12. A cylindrical gear box or 65 casing 20 is mounted on the movable cover member 12 and is provided with a cover 21, ordinarily securely fixed in position. The dolly shaft 19 extends through the gear box 70 75 and the cover 21 and is arranged eccentrically relative thereto. The dolly shaft 19, which carries suitable agitating devices on its lower end within the tub, is formed angular in cross-section and is adapted for 80 vertical movement relative to the gear box 85 20 and cover 21, to regulate the position of the agitating devices, in accordance with the size of the load contained in the tub.

75 A head 22 is secured to the upper end of the dolly shaft 19, above the cover 21, and 90 limits downward movement of said shaft. A gear case or housing 23 is mounted on the fixed cover member 11 and surrounding the shaft 15, and a countershaft 24 passes from 95 said gear case to the gear case 20. A spiral gear 25 is mounted on and fixed to the driving shaft 15 within the case 23 (see Fig. 3) and is in mesh with and adapted to drive a spiral gear 26 mounted loosely on the end of the countershaft 24. A clutch member 27 100 is fixed to the spiral gear 26 and is adapted to be engaged at times by a clutch member 28 feathered to the countershaft 24. The clutch member 28 is movable into and out of engagement with the clutch member 27 by 105 means of a lever 29 fulcrumed on a pin 30 extending through the casing 23, said lever having one end seated loosely in a circumferential groove 31 in said clutch member 28, and the opposite end extending outside 110

of said casing. A bevel gear 32 is mounted on and fixed to the opposite end of the countershaft 24 within the gear box 20, and said bevel gear meshes with and is adapted to 5 drive bevel gears 33, 34 mounted in horizontal position in said casing on opposite sides of the gear 32. The lower bevel gear 34 is supported on an annular shoulder 35 formed on the lower portion of the side wall 10 of the casing 20, and the upper gear 33 is supported on the top of said side wall and is held in place by the cover 21. A sleeve 36 is mounted in upright position within the gear box 20 and is formed with a longitudinal bore corresponding and fitted to the 15 shaft 19. The sleeve 36 is formed with outwardly projecting arms 37, 38 adjacent its top and bottom respectively, and said arms are adapted to engage successively and alternately with lugs 39, 40, respectively, formed on and projecting radially of the bevel gears 33, 34, which gears are of ring or annular form. As the gears 33, 34 are on opposite sides of the bevel gear 32 and are driven in 20 opposite directions, this alternate engagement with the sleeve 36, which is rendered possible because of the off-center arrangement thereof, results in an alternating rotary motion of the sleeve and consequently 25 of the dolly shaft 19. The lugs 39, 40 are so arranged on the gears 33, 34 that they alternately traverse that segment of the gear case 20 nearest the sleeve 36, and are thus designed for alternate engagement with 30 their corresponding arms, 37, 38, of said sleeve. The length and arrangement of the arms 37, 38 and lugs 39, 40 is such that each arm is in engagement with its lug for a trifle less than one-half of the revolution 35 of the gears 33, 34, and disengages because of the eccentric arrangement, by slipping off the end of the lug, just before the other arm comes into engagement with its lug. Spaced stops 41, 42 are fixed to and project 40 upwardly from the bottom of the box 20 and are adapted to be engaged alternately by the arm 38 of the sleeve 36, to insure stopping of the sleeve and the dolly shaft, at the end of each engagement of an 45 arm 37, 38 with its lug.

A wringer 43 is mounted on the support 10 and is adapted to be driven by the power shaft 15 through gears located in casings 44, 45 carried by said support. These elements and others shown in connection therewith form no part of my present invention 55 but are illustrated and described in detail in my companion application executed on even date herewith and pending concurrently in the Patent Office.

This mechanism is simple in construction, having a relatively small number of gears and other parts; is direct and positive in its operation; and operates with quietness 60 to a remarkable extent. When the machine

is loaded and running, scarcely any noise can be detected beyond the humming of the motor.

All of the gears are inclosed in the various housings, and there is absolutely no danger of the operator having his fingers or clothing caught or injured in any manner.

I claim as my invention—

1. A driving mechanism, comprising a power shaft, a countershaft, releasable gear connections between said shafts, a dolly shaft mounted for rotary oscillation, a bevel gear on said countershaft, bevel gears mounted for rotation on opposite sides of the first bevel gear and arranged eccentrically relative to said dolly shaft, and means for alternately connecting said latter bevel gears to the dolly shaft. 75

2. A driving mechanism, comprising a power shaft, a countershaft geared to said power shaft and adapted to be disconnected therefrom at times, a cylindrical gear case, a dolly shaft mounted for rotary oscillation through and eccentrically of said gear case, a bevel gear on said countershaft within said gear case, opposing bevel gears mounted for rotation and adapted to be driven by the first bevel gear, and means for alternately connecting said latter bevel gears to the dolly shaft. 80

3. A driving mechanism, comprising a power shaft, a countershaft releasably connected thereto, a cylindrical gear case, a dolly shaft mounted for rotary oscillation and arranged eccentrically relative to said gear case, a bevel gear on said countershaft within said gear case, opposing bevel gears mounted for rotation in said gear case and adapted to be driven in opposite directions by the first bevel gear, and arms on said dolly shaft in the planes of the opposing bevel gears, said bevel gears being formed with lugs adapted to be engaged by said arms alternately. 95

4. A driving mechanism, comprising a power shaft, a countershaft releasably connected thereto, a cylindrical gear case, a dolly shaft mounted for rotary oscillation and arranged eccentrically within said gear case, a bevel gear on said countershaft 100 within said gear case, opposing bevel gears mounted for rotation in said gear case and adapted to be driven in opposite directions by the first bevel gear, and arms on said dolly shaft in the planes of the respective opposing bevel gears, said bevel gears being formed with lugs adapted for alternate engagement with said arms, said gear case being formed with stops for alternate engagement by the lower arm of said dolly shaft. 105

5. A driving mechanism, comprising a power shaft, a countershaft releasably connected thereto, a cylindrical gear case, a dolly shaft mounted for rotary oscillation and vertical adjustment and arranged eccen- 110

- trically through said gear case, a bevel gear on said countershaft within said gear case, opposing bevel gears mounted for rotation in opposite directions within said gear case 5 and in mesh with the first bevel gear, and a sleeve mounted on and for rotation with said dolly shaft, radial arms on one side of said sleeve and vertically spaced, the opposing bevel gears being formed with radial lugs 10 adapted for alternate engagement with said radial arms.
6. A driving mechanism, comprising a power shaft, a countershaft at right angles thereto, intermeshing spiral gears on said 15 power shaft and countershaft, a dolly shaft mounted for rotary oscillation, gears arranged eccentrically relative to said dolly shaft and driven in opposite directions by said countershaft, and means connected with 20 said latter gears for alternate engagement with said dolly shaft, whereby said dolly shaft is alternately rotated in opposite directions.
7. A driving mechanism, comprising a 25 power shaft, a countershaft at right angles
- thereto, a spiral gear on said power shaft, a spiral gear meshing with the first spiral gear and adapted to be clutched to said countershaft, a dolly shaft mounted for rotary oscillation, and means connected with said 30 countershaft for alternate engagement with said dolly shaft, said means being arranged eccentrically relative to said dolly shaft, whereby said dolly shaft is alternately rotated in opposite directions. 35
8. A driving mechanism, comprising a power shaft, a countershaft at right angles thereto, intermeshing spiral gears on said power shaft and countershaft, a dolly shaft mounted for rotary oscillation, and means 40 connected with said countershaft for alternate engagement with said dolly shaft, whereby said dolly shaft is alternately rotated in opposite directions. 45

Signed by me at Clarinda, Iowa, this 18th day of April, 1914.

LEVI BROWN.
